UNITED STATES PATENT OFFICE.

GILBERT L. CROWELL, JR., OF ARLINGTON, NEW JERSEY, ASSIGNOR TO
DOMINICK & HIAFF, OF NEW YORK, N. Y.

DESIGN FOR A PATTERN FOR METAL STOCK.

SPECIFICATION forming part of Design No. 24,933, dated November 26, 1895.

Application filed October 5, 1895. Serial No. 564,811. Term of patent 7 years.

To all whom it may concern:

Be it known that I, GILBERT L. CROWELL, Jr., a citizen of the United States, residing at Arlington, in the county of Hudson and State 5 of New Jersey, have invented and produced a new and original Design for a Pattern for Metal Stock, of which the following is a description, reference being had to the accompanying drawings, which illustrate the design.

Figure 1 of the drawings shows a front elevation of a strip of metal stock bearing the design of my pattern, and Fig. 2 shows an enlarged cross-section of the same along the 15 line *a a*.

The design consists of a strip or ribbon of metal stock bearing the representation of several bands A, of curved form, running in parallel undulations, and also bearing obliquely-arranged groups of flowers and leaves B and C, recurring at regular intervals.

The essential features of the design are those above indicated.

What is claimed as new is—

The design for a pattern for metal stock, 25 substantially as shown and described.

GILBERT L. CROWELL, JR.
